AUTOMATIC MAIL DISPATCH AND PICKUP

John Vano, Chicago, Ill.

Application June 27, 1938, Serial No. 216,138

1 Claim. (Cl. 258—6)

My invention relates to mail cars, and includes among its objects and advantages the provision of an improved automatic mail dispatch and pickup for handling mail bags.

5 An object of my invention is to provide a device of a type described, in which means are employed for automatically discharging one or more mail bags while the train is in motion, and in which the discharge means is so constructed as to constitute an effective pickup for one or a large number 10 of mail bags from a catcher arm located along the railroad.

A further object is to provide a device of the type described which is so designed as to be applicable to cars of standard construction.

15 With these and other objects in view, this invention consists in certain novel features of construction, combination and arrangement of parts to be hereinafter more fully described and 20 claimed.

For a complete understanding of my invention, reference is to be had to the following description and accompanying drawings, in which

Figure 1 is a fragmentary elevational view of 25 a mail car showing my invention applied thereto;

Figure 2 is a sectional view along the line 2—2 of Figure 1;

Figure 3 is a similar view illustrating the pickup 30 up in its operating position;

Figure 4 is an inside elevational view of a portion of the invention;

Figure 5 is a side view of the structure of Figure 4 illustrating the pickup in its operating position;

Figure 6 is a view taken from the position indicated by line 6—6 of Figure 5;

Figure 7 is an enlarged view taken from the position indicated by the line 7—7 of Figure 1;

40 Figure 8 is a sectional view along the line 8—8 of Figure 7; and

Figure 9 is a cross sectional view of a portion of a mail car showing the part of the operating mechanism.

45 In the embodiment selected to illustrate my invention I make use of the usual mail car 10 provided with wheels 11 which run on the usual rails 12. In Figures 1 and 3, I indicate the usual catcher arm structure at 13, which supports a 50 plurality of mail bags 14 to be delivered to the mail car 10 under motion. Figure 3 illustrates the catcher at 15 positioned for picking up the mail bags 14. Normally the catcher 15 lies inside the mail car in a vertical position, as illustrated in Figure 2. Two catchers 15 are illus-

trated. While two units are illustrated, the invention operates equally well with a single unit. Since both units are identical in construction, the description of one will apply to both.

5 In Figures 4, 5, and 6, I illustrate the specific construction of the catcher 15 which also constitutes a mail bag dispatch or discharging unit for dropping mail bags from the car while in motion. In Figure 5 the mail car 10 includes an opening 16 constituting a door for the catcher 15. The catcher is hinged at 17 to the wall structure 18 of the mail car. Because of the hard usage to which the catcher is subjected, I prefer to extend the hinge 17 the full width of the wall 19 of the catcher.

15 Catcher or receptacle 15 includes a rear wall 20 and an inner wall 21 which curves inwardly, as at 22. Wall 19 is open at 23 to constitute a discharge opening located inside the mail car for delivering picked-up mail bags to the car.

20 The end 24 of the catcher 15 is open, which is also true of the side 25, which is the side approaching the mail bags 14 on the catcher arm structure 13. Side 25 of the catcher 15 includes a short wall 26 at the inner end of the catcher.

25 Within the catcher 15 I secure a diagonal wall, or partition 27, which constitutes a deflecting element for the mail bags being picked up. Partition 27 constitutes a bottom or support for the mail bags 28 loaded in the catcher for dispatching or discharging purposes. Inside the catcher 15, adjacent the wall 19, I mount an angular floor 29, which acts to more easily eject the mail bags 28 from the catcher when the latter is pivoted to the full line position of Figure 5.

30 In Figure 4 the rear wall 20 and the short wall 26 are bored to receive the trunnions 30 carried by U-shaped link 31. Link 31, when shifted to the full line position of Figure 5, pivots the catcher 15 from the dotted to the full line position. When 35 the link 31 is moved downwardly to the dotted line position of Figure 5, the catcher 15 takes the normal position inside the car, as illustrated in the dotted lines of Figure 5.

35 Between a metal plate 32 and the wall structure 18 I rotatably mount a grooved wheel 33 around which I run a cable 34. The vertical runs 35 of the cable 34 run around grooved wheels 36 rotatably mounted to the floor structure 37 of the mail car. The floor structure is provided with 40 a suitable opening for accommodating the vertical runs of the cable, as well as the grooved wheels 36.

45 To one of the vertical runs 35 I fixedly connect an arm 38 which operates along a vertical 50

slot 39 in the plate 32. The U-shaped link 31 is pivotally connected at 40 with the arm 38. Thus, movement of the cable 34 will impart movement to the U-shaped link 31 which in turn causes pivotal motion of the catcher 15. The ends of the cable 34 are connected at 41 with a diamond-shaped plate 42 rotatably mounted on a vertical shaft 43 carried by a casting 44 secured to the floor structure 37 of the mail car. Casting 44 may be made secure in any suitable manner, such as by bolts 45. I interpose relatively strong coil springs 46 in the diverging runs 47 of the cable 34 (see Figure 7).

Plate 42 includes right angular ears 48 to which I pivotally connect at 49 the parallel reaches 50 of an actuating member 51. The parallel reaches 50 constitute continuations of the converging reaches 52 which terminate in a single extension 53 provided with a free rolling sleeve 54. Sleeve 54 is located underneath a bar 55 having one end pivotally connected at 56 with the angular arm 57 of a lever 58. The lever is pivotally mounted at 59 to the floor structure 37. The opposite end of the bar 55 is pivotally connected at 60 with one end of a link 61 pivotally connected at its opposite end with a support 62 anchored to the floor structure 37 in any suitable manner such as by bolts. Link 61 parallels the angular arm 57 so that when the lever 58 is moved in the direction of the arrow 63, of Figure 9, the bar 55 will be lowered for pivoting the actuating member 51 about its axis 49.

In Figure 7 I illustrate the parallel reaches 50 as including diverging continuations or reaches 64 and 65. A cross bar 66 inter-connects the reaches 50 for strengthening purposes. According to Figures 2 and 3, the reaches 64 and 65 normally parallel the road bed and are positioned above the rails 12 at sufficient distances to insure proper clearance. Figure 7 illustrates the normal position of the actuating member 51 with the mail car traveling in the direction of the arrow 67, at which time the catcher 15 is positioned according to the dotted line illustration of Figure 5. An upstanding post 68 is fixedly anchored in the road bed a short distance from the outer side of one of the rails 12. Post 68 may be provided with a rotatable sleeve 69 arranged to contact the reach 65.

As the reach 65 strikes the post 68, the actuating member 51 is pivoted in the direction of the arrow 70, which pivotal action imparts movement to the cable 34 with the vertical run 35 connected with the link 31 moving in such direction as to rapidly move the link from the dotted to the full line position of Figure 5, which simultaneously causes the catcher 15 to be pivoted to a horizontal position preparatory to picking up the mail bags 14. Pivotal movement of the catcher 15 from the dotted to the full line position of Figure 5 is rapid, and as the catcher moves into a horizontal position, the mail bags 14 are discharged from the catcher. At the same time, the catcher is located in pickup relation with the mail bags 14 attached to the catcher arm structure 13. Within the catcher 15 I secure a pickup bar 71, which facilitates delivery of the mail bags 14 into the catcher. As the mail bags strike the deflecting plate or partition 27, the bags are deflected inwardly of the catcher 15, while the curved wall 22 deflects the bags inwardly in the

direction of the floor of the mail car. After the bags 14 have been picked up, the reach 64 of the actuating member 51 engages the post 72, anchored in the road bed slightly beyond the other rail 12. Post 72 may be provided with a rotatable sleeve 73 corresponding to the sleeve 69. Through engagement of the reach 64 with the post 72, the cable 34 is again actuated for moving the catcher 15 from the full to the dotted line position of Figure 5. Catcher 15 is provided with stops 74 which are arranged to engage the inner face of the wall structure of the mail car to prevent outward pivotal movement beyond the full line position of Figure 5. According to the arrangements of the posts 68 and 72 of Figure 7, it is obvious that the system will operate in the same manner with the train moving in the opposite direction.

While the posts 68 and 72 are permanently anchored in the road bed, I provide means for rendering the actuating member 51 inoperative. Figure 9 illustrates the normal position of the lever 58, at which time the bar 55 is in its elevated position. By moving the lever 58 in the direction of the arrow 63, the bar 55 will be lowered for pressing the shaft 53 downwardly and pivoting the actuating member 55 about its axis 49. Such pivotal action elevates the reaches 64 and 65 sufficiently far to bring them out of the path of the posts 58 and 72, thus permitting the train to pass beyond the posts without setting the discharging and pickup mechanism in operation. While I have illustrated two catchers 15 in connection with Figures 2 and 3, it is obvious that the invention will operate in the same manner with the car provided with one catcher only. Springs 46 operate to dampen the impact incident to impacting relation between the reaches 64 and 65 and the respective posts.

In the event that the mail car 10 is provided with one catcher 15 only, the door 16 associated with the car wall 75 may be closed, as at 76. Across the upper part of each door, I hinge a narrow wall part 77. Thus, the mail boxes may be stacked high in the receptacle with no danger of their catching on the fixed wall.

What is claimed is:

In combination with a mail car, a mail pouch receptacle pivotally mounted on one wall of the mail car, said receptacle including a mail pouch collector and discharger, said receptacle and the collector normally lying inside the mail car adjacent said one wall and the latter being provided with a door to permit the receptacle and the collector to be pivoted to a position exteriorly of the mail car, an actuating member pivotally connected with the mail car underneath the same, an operating connection between the actuating member and the receptacle and collector, means spaced along the road bed and cooperating with said actuating member for moving the receptacle into discharging position and bringing the collector into a pickup position with respect to mail pouches mounted on a catcher arm along the highway, means for shifting the actuating member into an inoperative position with respect to said means, and shock absorbing means interposed in said operating connection, said collector including means for deflecting mail bags downwardly inside the mail car.

JOHN VANO.
